UNITED STATES PATENT OFFICE.

RALPH C. THOMPSON, OF ATTLEBORO, MASSACHUSETTS.

DESIGN FOR A BADGE WITH RIBBON CORDON AND SLIDE.

45,164.

Specification for Design.

Patented Jan. 13, 1914.

Application filed November 15, 1913. Serial No. 801,267. Term of patent 3½ years.

To all whom it may concern:

Be it known that I, RALPH C. THOMPSON, a citizen of the United States, residing at Attleboro, in the county of Bristol and State of Massachusetts, have invented a new, original, and ornamental Design for a Badge with Ribbon Cordon and Slide, of which the following is a specification, reference being had to the accompanying drawing, forming part thereof.

The figure is a plan view of a badge with ribbon cordon and slide, showing my new design.

I claim:

The ornamental design for a badge with ribbon cordon and slide, as shown.

RALPH C. THOMPSON.

Witnesses:

MARY L. MCKENNA,
HELEN DUMICAN.
